UNITED STATES PATENT OFFICE.

ERNEST K. ARMSTRONG, OF MILLERSBURG, OHIO.

HAIR-PIN.

1,308,833.

Specification of Letters Patent. Patented July 8, 1919.

Application filed October 16, 1918. Serial No. 258,477.

To all whom it may concern:

Be it known that I, ERNEST K. ARMSTRONG, a citizen of the United States, residing at Millersburg, in the county of Holmes 5 and State of Ohio, have invented certain new and useful Improvements in Hair-Pins, of which the following is a specification.

My invention relates to improvements in hair pins, and more particularly to that 10 class or type which is formed of a single length of wire bent upon itself to form a two-armed or forked hair pin, such as is in common use, the present embodiment of this invention being designed not only as a 15 substitute for but an improvement on such pins, as will hereinafter more fully appear.

The primary object of the invention is to provide a generally improved hair pin of 20 this class, which will be exceedingly simple in construction, cheap of manufacture, and efficient in use.

A further object of the invention is to improve the construction and arrangement of the arms or prongs of the improved pin 25 whereby the improved pin may be more readily inserted, as well as removed, from the hair of the wearer.

A still further object is the provision of improved anchor shoulder members terminating in spaced prongs, the common planes of the latter being off-set to one side of the common plane of the shank or handle members, the shank shoulder and prong members being of similar form and arrangement 35 so as to extend parallel to each other when in closed or compressed position through the improved operating loop head, thereby greatly facilitating the insertion and removal of the hair pin in actual service.

40 A still further object is the provision of an improved handle or operating loop head whereby the arms or prongs may be readily compressed into parallel relation to each other for insertion in the hair of the wearer, and after being inserted may be readily released or expanded for being anchored or securely retained therein, and when desired may be compressed into released or parallel relation to each other for ready removal 45 from the hair.

With the above mentioned and other ends in view, the invention consists in the novel construction, arrangement, and combination or parts, hereinafter described, illustrated in 50 one of its embodiments in the accompanying

drawings, and particularly pointed out in the appended claims.

Referring to the accompanying drawings, forming a part of this specification, Figure 1, is a side elevation of the improved hair 60 pin in its normal or anchored position, and illustrating the relative position and operation of the parts after being inserted and expanded in the hair of the wearer.

Fig. 2, a similar view, illustrating the 65 manner in which the arms or prongs are compressed into parallel relation to each other through the improved operating loop head in the act of inserting the same into or removing the same from the hair of the 70 wearer.

Similar numerals of reference designate like parts throughout all the figures of the drawings.

The improved hair pin comprises a single 75 length of wire bent upon itself midway between its ends forming a handle loop head 1, carrying spaced arm or shank members 1^a, the latter terminating in anchor shoulders 1^b, extending in a like direction and to one 80 side, said shoulder members terminating in off-set prongs 1^c, the common axial planes of said off-set prongs 1^c, being at one side of the common axial plane of said spaced arm or shank members 1^a, as shown most clearly 85 in the drawings.

As a means of causing the shank shoulder and prong members to normally overlie or extend parallel with each other when closed or compressed through the medium of the 90 operating handle loop head 1, as shown most clearly in Fig. 2, of the drawings, for the ready insertion and removal of the hair pin in the hair 2, of the wearer, the shank shoulder and prong members are of like form and 95 extend in a like direction, and it will be obvious upon reference to Fig. 1, that when the shank shoulder and prong members are released by the handle loop head and permitted to expand into their normal expanded or 100 anchored position, as shown in Fig. 1, of the drawings, the anchor shoulders 1^b, will interlock with the hair so as not only to prevent the outward movement of the hair pin, but securely maintain the same in proper position as against inward movement.

It will also be observed that the handle loop head 1, is of such form and arrangement with respect to the shank and prong members as to enable the latter to be readily 110

manipulated through the thumb and finger of the hand, as shown most clearly in Fig. 2, of the drawings, such handle loop head being of convenient form to be readily grasped by the hand in the act of insertion and removal.

From the foregoing description, taken in connection with the accompanying drawings, the operation and advantages of my invention will be readily understood.

Having thus described one of the embodiments of my invention, what I claim and desire to secure by Letters Patent, is,—

1. A hair pin, comprising shank members terminating at one end in a prong operating loop head and at the other in anchor shoulders terminating in off-set prongs having their common axial plane disposed wholly at one side of and substantially parallel with the common axial plane of said shank members, said shank shoulder and prong members overlapping and extending

parallel with each other when compressed by said operating loop head for insertion into and removal from the hair of the wearer. 25

2. A hair pin, comprising shank members terminating at one end in an enlarged prong operating loop head and at the other in anchor shoulders the latter being spaced a substantial distance from said loop head and terminating in off-set prongs having their common axial plane disposed wholly at one side of and substantially parallel with the common axial plane of said shank members, said shank and prong members normally extending in diverging relation and being brought into overlapping parallel relation to each other when closed by said operating loop head for inserting into and removing from the hair. 30 35 40

In testimony whereof I have affixed my signature.

ERNEST K. ARMSTRONG.
